(57) **CLAIM**

The ornamental design for a display housing, as shown and described.

DESCRIPTION

FIG. 1 is a front isometric view of my new design.

FIG. 2 is a rear isometric view.

FIG. 3 is a front view.

FIG. 4 is a rear view.

FIG. 5 is a top view.

FIG. 6 is a bottom view.

FIG. 7 is a left side view.

FIG. 8 is a right side view.

FIG. 9 is a rear isometric view of an alternative embodiment of my new design. The front, left, right, and top are identical to those illustrated in FIGS. 3, 5, 7, and 8, respectively.

FIG. 10 is a rear view of the alternative embodiment; and, FIG. 11 is a bottom view of the alternative embodiment.
